UNITED STATES PATENT OFFICE.

MARQUERITE L. SOBRA, OF CHICAGO, ILLINOIS.

ASH-SIFTER.

1,080,854.

Specification of Letters Patent.

Patented Dec. 9, 1913.

Application filed April 2, 1912. Serial No. 687,999.

To all whom it may concern:

Be it known that I, MARQUERITE L. SOBRA, a citizen of the United States, residing at Chicago, in the county of Cook and State 5 of Illinois, have invented certain new and useful Improvements in Ash-Sifters, of which the following is a specification, reference being had therein to the accompanying drawing.

10 This invention relates to ash receptacles and sifters, and has for its object the production of an efficient sifter which is made in a compact form so as to prevent the dust from the ashes from flying out of the receptacle.

15 Another object of this invention is the production of an efficient ash receptacle and sifter, the different sections of which may be separated so as to allow the ash receiving portion thereof to be readily detached from the sifter section, whereby the ashes may be conveniently dumped from the ash receiving section.

20 With these and other objects in view this invention consists of certain novel constructions, combinations, and arrangements of parts, as will be hereinafter fully described and claimed.

25 In the drawings: Figure 1 is a perspective view of the receptacle and sifter. Fig. 2 is a central vertical section. Fig. 3 is a section taken on the line 3—3 of Fig. 2. Fig. 4 is an enlarged detail view of the door mechanism for controlling the outlet from the 30 sifting cylinder. Fig. 5 is an enlarged front elevation of the means for holding the doors of the receptacle in a closed position. Fig. 6 is a detail perspective of a modified form 35 of the invention showing the ash receptacle and sifter of a cylindrical form.

40 By referring to the drawings, it will be seen that the ash receptacle may either be made of a rectangular or cylindrical structure and this receptacle comprises a lower ash receiving section 1, and an upper sifter 2. The lower ash receiving receptacle 1 has its bottom provided with inclined walls 3 for preventing the ashes from collecting along the lower edge of the receptacle and also 45 preventing the bottom receptacle from being battered by coming in contact with foreign objects. The section 1 is supported upon the rollers 4 for facilitating the conveyance of the ash receptacle from place to place. A 50 rim 5 passes around the upper edge of the lower section 1, and extends for a short dis-

tance above the upper edge of the section 1 to form a protector rim for holding the upper sifter section 2 in a correct position upon the upper edge of the lower section 1. This 55 rim 5 may be held upon the section 1 by means of rivets or other suitable fastening means. A hook 6 is carried upon the front and rear of the section 1 near the upper edge thereof, and this hook comprises the 60 laterally extending ear 7 which ear is provided with a socket 8 for constituting means to be engaged by the bail of a bucket or coal scuttle for supporting the coal scuttle upon the body of the ash receptacle. One of the 65 hooks 6 is placed directly under the cinder or coal discharge opening 9, and this hook is adapted to receive the bail of the bucket or coal scuttle to receive the cinders or coal as the same are discharged from the sifting 70 screen.

75 The upper sifter section 2 of the ash receptacle, as stated above rests upon the upper edge of the lower section 1, and is provided with a coal discharge opening 9, which 80 opening is adapted to be closed by means of a vertically sliding door 10. This sliding door 10 works in a pocket 11 carried by the inner face of the receptacle 1, and the door 10 is provided with a knob 12. This 85 knob 12 is indicated by means of a pivoted hook 13 which fits around the reduced shank of the knob 12 and holds the door in a closed position. An opening 14 is formed in the lower section 1, and this opening is 90 closed by means of a door 15, which door is held in a closed position by means of a hook 16 engaging the knob 17 similar to that described in connection with the door 10. The opening 14 is so provided in the lower 95 section 1 as to allow easy access to be had to the lower section of the receptacle without removing the upper section therefrom.

100 A sifting cylinder 18 is rotatably mounted upon a shaft 19, which shaft is operated by means of a crank 20. This sifting cylinder 18 is formed of wire mesh or may be formed of any other desired material for accomplishing the purpose and this wire mesh is reinforced at its outer end by means of a cylindrical band 21 and constituting a rim. The inner end of the cylinder 18 is reinforced by means of a cylindrical band 22, and this band 22 is braced by means of 105 diagonally extending braces 23 which braces engage the inner edge of the band 22 and engage a collar 24 carried by the shaft 19.

- The band 22 is mounted, and travels within a band 25 supported within the upper section 2, and this band 25 constitutes a guiding means for the sifting cylinder 18 and holds the same against lateral play within the section 2. This band 25 is dependent from the lower edge of the wall 26 which wall constitutes a bottom for the receptacle 27, which receptacle 27 is formed near the top of the section 2 of the ash sifting portion. A partition 28 is formed at the end of the compartment 27 so as to seal the same against the entrance of dust from the ashes, and the upper end of this compartment 27 is closed by means of an upwardly swinging door 29. This receptacle may be used to hold gloves or tools if so desired, or the operator may place his lunch therein without fear of the same becoming corroded with dust from the ashes.
- A locking rib 30 is formed upon the door 29 and this locking rib engages the edge of the overhanging flange 31 on the top of the section 2 for normally holding the door 29 in a closed position. The section 2 is provided upon its rear with an inclined surface 32 which constitutes an entrance opening for the ashes to be emptied in the ash receptacle or upon the ash sifting screen. This ash entering opening 32 is normally closed by means of an upwardly swinging door 34 which door is normally held in a closed position by means of a locking rib 35 formed near the lower edge of the door 34. A sifting screen 36 is positioned directly below the opening 32, and extends from the rear wall of the section 2 to the edge of the rim 22 of the sifter 18. This sieve 36 is supported by means of inclined wall flanges 37, which flanges direct the ashes toward the sieve 36 as the same are emptied through the ash opening 32. It should be understood that as the ashes are emptied into the ash sifting section considerable of the loose ashes will fall through the screen of the sifter 36 but the ashes which are more compact will slide down upon the sifter 18, and by rotating the sifter, the same will be agitated so as to allow the loose ashes to be readily disintegrated from the cinders. An article supporting band 38 is carried near the upper end of the section 2 of the ash sifting receptacle and this band is provided with outwardly projecting, upwardly extending hooks 39 upon which hooks may be hung shovels, tools or any article desired, thereby making it possible to have the ordinary tools of necessity in such a place as to allow easy access to be had thereto.
- As illustrated in Fig. 6, and as previously explained, this receptacle may be made of any desired shape, and by referring to Fig. 6, it will be seen that the same comprises a lower section 1^a and an upper sieve containing section 2', the lower section 1^a having

an inclined lower edge 3' for preventing ashes from congregating in the corners of the receptacle 1^a, and for preventing the battering of the receptacle at its lower end, which would be likely to cause the receptacle to become worn and perhaps broken, thereby allowing the ashes to drop out upon the floor. 70

The hooks 7 may be used as handles to lift the device, and facilitate the carrying of the same from place to place. A widened web portion is formed adjacent to the hook 7 as indicated in Fig. 1 for directing the coal or cinders from the discharge opening to prevent the cinders or coal from dropping over the side edges of the receptacle adapted to receive the cinders. 75 80

Of course, it should be understood that this invention may be modified in its detail mechanical construction without departing from the spirit of the invention. 85

As illustrated in Fig. 2, and as previously stated in the above specification, it will be seen that the widened portions formed adjacent the hook 7 will constitute a continuous chute for directing the cinders into the receptacle which is adapted to be supported by the hook 7, and that these widened portions will direct the cinders into the receptacle and prevent the cinders from dropping over the sides thereof. 90 95

What is claimed is:—

1. A receptacle of the class described comprising a base and an upper ash sifting section, said ash sifting section provided with a cinder discharge opening, a door slidably mounted within said base of said lower section and capable of being moved upwardly to close said cinder discharge opening, and means carried by said ash sifting section for holding said door in a closed position upon said discharge opening. 100

2. A receptacle of the class described comprising a body, a sifter carried by the upper end of said body, said body provided with a cinder discharge opening in substantial alinement with the lower wall of said sifter, and bucket supporting means supported adjacent said cinder discharge opening in substantial alinement with said discharge opening and the lower wall of said sifter and constituting a continuation of the discharge opening and sifter for guiding cinders into a bucket adapted to be carried by said bucket supporting means. 110 115

3. A receptacle of the class described comprising a body, a sifter carried by said body, said body provided with a discharge opening in substantial alinement with the lower wall of said sifter, a bucket supporting hook carried adjacent said discharge opening and in substantial alinement with the bottom of said opening and the bottom wall of said sifter, said bucket supporting hook provided with a supporting notch adjacent its outer 120 125 130

end adapted to receive the bail of a bucket, and means formed adjacent said hook for directing cinders into a bucket adapted to be carried thereby.

5 4. A receptacle of the class described comprising a lower section and an upper section, said upper section provided with a sifter, said upper section provided with a cinder discharge opening in alinement with the bottom wall of said sifter, a bucket supporting hook carried by said lower section in substantial alinement with the lower edge of said discharge opening and the lower wall of said sifter, and means formed adjacent said hook for directing cinders into a bucket adapted to be carried thereby as the cinders are discharged from the discharge opening in said upper section.

10

15

5. A device of the class described comprising a casing, a rotating screen carried by said casing, said casing provided with a discharge opening, a door for closing said discharge opening, a receptacle supporting hook formed below said discharge opening and provided with widened flanges for constituting a continuous discharge chute from said receptacle for delivering cinders into a receptacle adapted to be supported by said hook.

In testimony whereof I hereunto affix my signature in presence of two witnesses.
